UNITED STATES PATENT OFFICE.

ADOLF HOFFMAN, OF LACKAWANNA, NEW YORK.

COMBINATION LOCK.

Application filed May 18, 1923. Serial No. 639,821.

To all whom it may concern:

Be it known that I, ADOLF HOFFMAN, a citizen of the United States, residing at Lackawanna, county of Erie, and State of New York, have invented certain new and useful Improvements in Combination Locks, of which the following is a specification.

This invention relates to improvements in locks and it is the principal object of the invention to provide a lock for attachment to closures, doors, trunks or the like in order to prevent other than the proper persons from opening or unlocking the said closure, door or trunk.

Another object of the invention is to provide a lock provided with a plurality of locking elements which are independently operable which ensure a locking of the closure so that the locking elements can only be disengaged from their respective keepers by the person acquainted with the precise operation and combination of the various parts of the lock.

A further object of the invention is the provision of a key-operated lock which requires the use of the key in distinctly different ways to bring about its opening or closure, so that nobody not acquainted with its mechanism will be able either to unlock or to lock the lock.

These and other objects and advantages of my invention will become more fully apparent as the description thereof proceeds, and will then be specifically pointed out in the appended claims.

In the accompanying drawings forming a material part of this disclosure:

Figure 1 is a front view of a lock constructed according to the present invention.

Figure 2 is a similar view after removal of the top plate of the lock.

Figure 3 is a front view of the inner mechanism of the lock after removal of the inner top plate, partly in section along line 3-3 of Figure 6 showing the lock locked.

Figure 4 is a longitudinal section through the lock on line 4-4 of Figure 5.

Figure 5 is a view similar to Figure 3 with the lock unlocked.

Figure 6 is a cross-section on line 6-6 of Figure 3.

Figure 7 is a section on line 7-7 of Figure 5.

Figure 8 is a detail view of a key.

55 The lock comprises the ordinary casing

10 adapted to be inserted into a door 11 provided at its front with an ornamental key hole plate 12 attached to the front face of the door by means of nails 13 or any other suitable fastening means and showing 60 key holes 14 and 14', while the jamb 15 of the door carries a keeper plate 16 provided with a plurality, for instance as shown, three, perforated keeper lugs 17, 18 and 19, adapted to extend into the lock casing 65 through the slots 20, 21, 22 in the side wall of the casing.

Spaced from the front wall of the casing, a top plate 23 is secured to the rear wall 24 of the casing by means of screws 25, 26, 70 and 27 entering sockets 28, 29 and 30 respectively, correspondingly mounted on rear wall 24 of the casing.

This plate 23 is provided in its inner edge with recesses 31, 32, and 33 respectively, into which the keeper lugs 17, 18 and 19 extend as shown in Figure 2.

The top plate carries upstanding, rotatable key-hole sockets 34 and 35 with foot flanges engaging the lower face of plate 23, and provided with slotted and recessed foot parts 36 and 37 rotating on the upper face of the plate. These foot parts are equipped with arcuate slots 38, 39 and 40, 41 in which pins or screws 42, 43 and 44, 45 respectively are guided to limit the rotary movements of sockets 34 and 35 in one or the other direction.

The foot part 37 has a shouldered part 46 formed into a knife edge, and the foot part 36 has a rounded or curved shoulder 47, while the plate 23 near this shouldered part is provided with an inclined slot 48, in which a pin 49 is displaceable, which is depending from the lower end face of a 95 leaf spring 50, which is integral with a spring leaf 51 attached to the casing 10 by means of rivets 52, 53 and carries at its opposite end a leaf spring 54 which is similar to spring 50 and the lower outer edge 100 of which is adapted to be engaged by knife edge 46 adapted to lift spring 54.

The leaf springs 50 and 54 carry at their lower faces depending pins 55 and 56 adapted to pass through openings in plate 23 105 for a purpose hereafter more fully to be described.

A bolt 57 is sliding between the foot parts 36 and 37 on top of plate 23 and is guided thereon by means of lugs 58, 59 110

on plate 23 which engage into slots 60 and 61 of bolt 57.

The plate 23 is also provided with an arcuate or curved slot 62 near the left hand end of foot part 36 in which a depending pin 63 of this foot part is displaceable, to which one end of a spring 64 is attached to a pin 65 secured to the lower face of plate 23, to which is also secured one end of a spring 66 attached with its other end to a pin 67 depending from latch 57 and guided within a slot 68 of plate 23. Another spring 69 is secured at one end to a pin 70 depending from plate 23, while its other end is attached to a pin 71 depending from foot part 37 and working in a slot 72 of plate 23. One end of latch 57 has a shoulder 73 adapted to engage shoulder 74 of foot part 37, while the opposite end of latch 57 has a finger 75 formed therewith having a curved outer edge adapted to slide along the similarly curved outer face of foot part 36 and roll itself off on the same.

To the inner face of the rear wall 24 of the casing and described above, the socket 29 is secured and to this socket is pivotally attached intermediate its ends, the pawl 76 provided with a hook 77 at its upper end adapted to engage the central keeper lug 18.

At its lower end the pawl 76 is pivotally secured, as at 78 to a plate 79 slidably guided on the inner face of the rear wall 24 by means of a pin 80 in the rear wall engaging in a slot 81 of plate 79, while a spring 82 wound intermediate its ends around pin 83 is pressing with one of its ends plate 79 downwards, while its other end is resting against socket 30. A pawl 84 secured to the inner end of a pin 85 is rotatable therewith, extends through the rear wall 24, and carries on the outside of the same an operating knob 86 by means of which the pawl 84 can be operated to engage a shoulder 87 of plate 79, while the rotation of the pawl 84 in the opposite direction is limited by a pin 88 in the rear wall 24.

An arm 89 is pivotally secured at its rear end to a pin 90 in the rear wall of the casting, and a spring 91 resting with one end against a post 92 in the rear wall engages a slot in the upper edge of arm 89 and tends to press the same downwardly. In its lower edge the arm is provided intermediate its ends with a shoulder 93 and near its lower end with a recess 94, while at its lowermost point its end is cut away as at 95.

A plate 96 is slidably arranged on top of arm 89, and is guided by means of the reduced upper ends 97 of post 92 and 98 of post 99 engaging into slots 100 and 101 in the plate. Plate 96 carries near its upper end a locking finger 102 adapted to engage keeper lug 17.

To a pin 103 on plate 96 a dog 104 is pivotally secured at one end, and a spring 105

wound intermediate its ends around a pin 106 on plate 96 engages with one end the outer upper end of dog 104 and tends to press the same outwardly so that the shoulder 107 at its other end engages a pin 108 on plate 96. The other end of spring 105 engages the edge of a pawl 108, which is pivoted intermediate its ends to a pin 109 on plate 96, and the outward movement of pawl 108 is limited by its engagement with a pin 110 on plate 96. The inner edge of pawl 108 is engaged by one end of a spring 111 wound intermediate its ends around a pin 112 on plate 96, while its other end engages a pin 113 also mounted on plate 96. The lower end of dog 104 is formed with a slot 114. The base plate 24 carries also two guide pins 115 and 116 adapted to be engaged in the longitudinal bore 117 of key 118 which is equipped with a bit 119 of any well known construction.

The arm 89, plate 96, dog 104, and pawl 108 are duplicated above pawl 76, are however directed in opposite directions and plate 96 carries an upper finger 120 adapted to engage keeper lug 19, and its inner edge is curved as at 121 in order to accommodate socket 29.

It is therefore believed a detailed description of these parts will not be required.

The lock operates in the following manner:

Supposing the lock is locked, as illustrated in Figure 3, and it is desired to open the same: The operator will insert the key into the upper key socket 34 and turn it clockwise until its bit is beneath inclined slot 48 (Fig. 6), he will then raise the key and its bit will lift pin 49 and leaf spring 50 as well as the pin 55 connected therewith. This pin, as shown in Figure 3 rests during the locked state of the lock in slot 114 of dog 104 locking the same against movement; the dog evidently will now be free to move laterally and outwardly under the action of spring 122, which at one end is secured in plate 96, while its other end presses against a pin 123 depending from the dog 104, so that its slot 114 comes out of the path of pin 55. When now the key is withdrawn from key hole 14 until the lower edge of its bit is in one plane with foot part 36 of socket 34 and the key is turned clockwise, it will rotate foot part 36 against the action of spring 64, while spring 66 will tend to press finger 75 of latch 57 into engagement with the shouldered part 124 of the foot part which will hold latch 57 in its upper position with its end or shoulder 73 disengaged from the shoulder 74 of foot part 37, allowing an operation of socket 35. Now the key is placed into the lower key hole 14 until its bit is in one plane with the foot part 37 and is then turned anti-clockwise, this movement will bring the knife edge 46

125 129 130

under leaf spring 54 and lift its pin 56 out of engagement with opening 114 in the lower dog 104.

This dog will now be free to move laterally outwards under the action of spring 125 secured at one end in plate 96 and with its other end engaging a depending pin 126 of dog 104.

The key is then again placed into key hole 14' and turned anti-clockwise so that its bit travels along curve 127 on the inner edge of arm 89 to displace this arm with its recess 94 out of engagement with pin 128 depending from plate 96.

15 A continued rotation of the key in the same direction will engage its bit with the inclined end 129 of dog 104 and will move this dog, and plate 96 somewhat upwards, as shoulder 107 of dog 104 is engaging pin 108 of plate 96. After the bit of the key has passed shoulder 129, a continued rotation of the key in anti-clockwise direction will engage its bit with the left hand edge of pawl 108 and carry the same and plate 96 upwards until pin 128 comes into engagement with shoulder 95 of arm 89 and finger 120 is out of engagement with keeper lug 19. The engagement of pin 128 with shoulder 95 will prevent a motion of the parts in either direction and the pawl 108 yielding under the continued pressure by the bit will turn around its pivot point 109 and will allow the passage of the bit of the key and a withdrawal of the same.

35 The upper part of the lock is now unlocked. The unlocking of the lower part is effected in a similar manner by the introduction of the key into key hole 14, and clockwise rotation of the same, so that its bit will engage the lower edge of plate 79 and press the same towards the top, which will disengage pawl 76 or its hook 77 respectively from the keeper 18. A continued rotation of the key will bring its bit into engagement with the left hand edge of arm 89 and displace the same towards the right, disengaging its recess 94 from pin 128 depending from plate 96. A continued rotation of the key in the same direction will bring its bit into engagement with the inclined end 129 of dog 104 and will move this dog and plate 96 somewhat downwards as shoulder 107 of dog 104 is engaging pin 108 of plate 96.

55 After the bit of the key has passed shoulder 129, a continued rotation of the key in clockwise direction will engage its bit again into engagement with the lower edge of plate 79 which in the meantime under the action of spring 82 has been displaced downwardly, and again lift the same. A continued rotation will now bring the bit of the key into engagement with pawl 108 and carry the same and plate 96 downwards until pin 128 comes into engagement with

shoulder 95 of arm 89 and finger 102 out of engagement with keeper lug 17. The engagement of pin 128 with shoulder 95 will prevent a motion of the parts in either direction. A continued rotation of the key 70 will then again bring its bit into engagement with the lower edge of plate 79 to press the same upwards against the action of spring 82 and will bring hook 77 of pawl 76 out of engagement with keeper lug 18 75 and the lock will be open. The plate 79 can be kept in its elevated position by an operation of pawl 84 by means of its knob 86 brings its side edge into engagement with the shoulder 87 of plate 79. 80

The locking of the lock is effected by the same operation in reversed order.

Having thus described my invention what I claim as new and desire to secure by Letters Patent of the United States is: 85

1. A lock including a pair of sliding bolts and a locking hook arranged between said bolts, means for normally locking the sliding bolts against displacement, means for operating the locking hook independently of the 90 sliding bolts, and independent key-operated sockets for releasing the locking means.

2. A lock comprising a pair of sliding bolts and a locking hook between both bolts, means for operating and locking said hook 95 independently of said sliding bolts, means for normally locking said sliding bolts against displacement, and a leaf spring carrying said locking means, a pair of rotatable key sockets, means for normally locking said 100 sockets against movement, and means for releasing said last named locking means and sockets by a key for releasing the locking means to allow the operation of the lock by 105 a key.

3. A lock comprising a pair of sliding bolts, a central locking hook between said bolts, means for operating said hook, perforated dogs on said bolts, a leaf spring comprising two plates, pins on said plates 110 adapted to enter the perforations of said dogs for normally locking said bolts, a pair of rotatable key sockets, a slotted base plate for said sockets, said pins adapted to be disengaged from said dogs by the lifting of 115 said plates by means of a key adapted to pass with its bit through the slot in said base plate, means for locking the sockets against rotation, and means for releasing said last named locking means upon the 120 lifting of said plates.

4. A lock comprising a pair of pivoted arms, a pair of sliding plates carrying locking fingers, a locking hook pivoted intermediate its ends between said sliding plates, means for manually operating said hook, means allowing an operation of said hook by means of a key bit, a pair of perforated dogs on said sliding plates, means for connecting arms and plates, pins for connecting 130

- dogs and plates, a pair of spring plates, pins on said plates adapted to engage the perforations of said dogs, a pair of rotatable key sockets adapted to allow an elevation 5 of said pins from the slots in said dogs to permit the unlocking of the lock, a sliding locking bolt for said sockets, and means for allowing a release of said bolt upon the elevation of said spring plates.
- 10 5. In a lock of the class described, an inner perforated and slotted top plate, two rotatable key sockets on said plate, foot flanges on said sockets, means for limiting the rotation of said sockets in either direction, leaf spring plates, a pin on one of said plates adapted to engage the slot in said top plate, a locking bolt for both sockets, a spring for normally pressing said bolt into its locking position and allowing a release 15 of both sockets upon the release of said spring plates by the operation of one of the sockets by a key.
6. In a lock of the class described, a central locking hook pivoted intermediate its ends, a recessed sliding plate to which the lower end of said hook is pivoted adapted to

be operated by the bit of a key for moving said hook into its locking position, a spring for pressing said plate to move the hook into its unlocking position, an operating knob 30 and a pawl on said knob adapted to engage in the recess of said plate for allowing a manual operation of said locking hook.

7. In a lock of the class described comprising a casing, a pair of recessed arms pivotedly secured at one of their ends to the base plate of said casing, a pair of recessed sliding plates, pins connecting and locking said plates to said arms, locking fingers on said plates, perforated dogs pivotally secured at one end to said plate shouldered at their opposite ends to engage pins on said plates, and means for normally locking said dogs and plates against movement, allowing a release of said plates and locking fingers 40 upon the operation of the lock by a key in the hands of a person knowing certain secrets.

In testimony whereof I have affixed my signature.

ADOLF HOFFMAN.
